US00D896178S

(12) **United States Design Patent** (10) Patent No.: **US D896,178 S**
(45) Date of Patent: ** Sep. 15, 2020

(54) **BASE OF MAGNETIC COMPONENT**

(71) Applicant: **DELTA ELECTRONICS, INC.**,
Taoyuan (TW)

(72) Inventors: **Yue Tsao**, Taoyuan (TW); **Chun-Ching Yen**, Taoyuan (TW); **Kun-Te Chen**, Taoyuan (TW); **Mingqiang Zhu**, Taoyuan (TW); **Jian Xu**, Taoyuan (TW); **Hsien-Chun Peng**, Taoyuan (TW); **Zhi-Liang Zhang**, Taoyuan (TW)

(73) Assignee: **DELTA ELECTRONICS, INC.**,
Taoyuan (TW)

(**) Term: **15 Years**

(21) Appl. No.: **29/635,738**

(22) Filed: **Feb. 2, 2018**

(51) LOC (12) Cl. **13-02**

(52) U.S. Cl.

USPC **D13/118**

(58) **Field of Classification Search**

USPC ..... D13/183, 101, 118, 119, 120, 121, 133, D13/147, 154, 165, 179, 180, 182, 199; 200/11 B, 11 D, 12; 204/155, 157.22; 307/401, 406, 415, 416

CPC H05K 7/00; H05K 9/0007; H05K 9/0075; H01F 5/02

(57) **CLAIM**

The ornamental design for a base of magnetic component, as shown and described.

DESCRIPTION

FIG. 1 is a perspective view of a base of magnetic component showing our new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The broken lines represent the portions of the base of magnetic component that forms no part of the claimed design.
